UNITED STATES PATENT OFFICE.

GEORGE LYMAN LILLY, OF JACKSONVILLE, FLORIDA.

CUT-OFF DEVICE FOR POWDER-BOXES.

1,178,401.

Specification of Letters Patent.

Patented Apr. 4, 1916.

Application filed November 10, 1914. Serial No. 871,419.

To all whom it may concern:

Be it known that I, GEORGE L. LILLY, a citizen of the United States of America, residing at Jacksonville, in the county of Duval and State of Florida, have invented new and useful Improvements in Cut-Off Devices for Powder-Boxes, Medicine-Containers, and the like, of which the following is a specification.

10 This invention relates to improvements in cut-off devices for powder boxes, medicine containers and the like and has particular application to a measuring cut-off device.

In carrying out the present invention it 15 is my purpose to provide a device of the class described which may be readily applied to any powder box or medicine container now in use and whereby the flow from the container will be automatically cut 20 off after the determined quantity has been discharged.

It is also my purpose to provide a device 25 of the class described which will be automatic in operation and which will embrace the desired features of simplicity, efficiency and durability coupled with cheapness of cost in manufacture and marketing.

With the above and other objects in view, the invention consists in the construction, 30 combination and arrangement of parts hereinafter set forth in and falling within the scope of the claim.

In the accompanying drawing; Figure 1 is a view in side elevation of a powder container equipped with a measuring cut-off device constructed in accordance with the present invention. Fig. 2 is an enlarged 35 vertical sectional view through the discharge spout of the powder container and the cut-off device thereon showing the parts in normal closed position. Fig. 3 is a view similar to Fig. 2 showing the parts in the position they occupy when the powder is discharged.

Referring now to the drawing in detail, 40 1 designates a powder container of any suitable or preferred construction. In the present instance, this powder container is provided with an upwardly extending discharge spout 2 by means of which the powder may 45 be discharged from the container when the latter is inverted.

My improved cut-off device is designated 50 as an entirety at 3 and, in the present instance, comprises a tube 4 designed to encircle the outer end of the spout 2 and of a cross sectional configuration corresponding

to that of the spout. In this instance, the tube 4 is substantially rectangular in cross section owing to the spout 2 being of this shape, and journaled in the opposite end 60 walls of the tube 4 and lying adjacent to the inner face of one of the side walls thereof is a rod 5, while a cover plate 6 has one edge suitably secured to the rod 5. This cover plate is of cross and longitudinal dimensions slightly greater than the corresponding dimensions of the tube 4 so that when the cover plate is in closed position it will overlap the outer edge of the tube 65 to effectively close the same. Also secured to the rod 5 and extending into the tube 1 in a plane at right angles to the cover plate 6 is a cut-off plate 7 of transverse and longitudinal dimensions equal to those of the tube and normally lying against the adjacent side wall of the tube and adapted to be moved across the tube when the cover plate 6 is swung to open position. Secured 70 to one end of the rod 5 and depending therefrom at an angle to the vertical is an arm 75 80 and connected with the lower end of the arm 8 is a weight 9.

In practice, the cover plate 6 normally extends across the tube 4 and so closes the spout 2. When, however, it is desired to discharge a quantity of the powder from the container, the latter is inverted and in this movement of the container the weight 9 swings the arm 8 and rod 5 with the effect 85 to move the cover plate 6 out of the path of the powder and the cut off plate 7 across the path of the powder. In this movement of the plates the quantity of powder between the same is discharged and the cut-off plate closes the tube 4, thereby preventing 90 further discharge of the powder. When the position of the container is reversed the weight 9 again swings the arm 8 in the reverse direction and so reciprocates the cover plate and cut-off plate to normal positions 95 so that the above operation may be repeated when the container is again inverted.

From the foregoing description taken in connection with the accompanying drawing, the construction, mode of operation and 100 manner of employing my improved measuring cut-off device will be readily apparent. It will be seen that when the container is inverted to discharge the contents thereof a predetermined quantity only of such contents is discharged. Although I have shown 110 and described the device as particularly

adapted for powder containers, I wish it to be understood that the same is equally applicable to liquid medicine containers and in practice the plates 6 and 7 may be so connected as to be capable of relative adjustment so that the quantity of material discharged from the container may be varied in accordance with the circumstances of the particular case.

10 While I have herein shown and described one preferred form of my invention by way of illustration, I wish it to be understood that I do not limit or confine myself to the precise details of construction herein described and delineated, as modification and variation may be made within the scope of the claims without departing from the spirit of the invention.

I claim:

20 A device of the class described comprising a tube angular in cross section, a rod journaled in said tube at one end thereof lying parallel with one of the walls of the tube, a

cover plate having one edge connected to said rod and normally lying across the adjacent end of the tube to close the latter, a cut-off plate connected to said rod and projecting into said tube normally parallel with the adjacent wall and arranged at right angles to said cover plate and movable across said tube in the movement of the cover plate to open position, an arm connected to one end of said rod and depending therefrom at an angle to the vertical and a weight on the free end of said arm acting to hold the cover plate and the cut-off plate in normal position and to swing the same out of such position when the tube is inverted.

In testimony whereof I affix my signature 40 in presence of two witnesses.

GEORGE LYMAN LILLY.
